[57] CLAIM

The ornamental design for a helmet for security personnel, as shown and described.

DESCRIPTION

FIG. 1 is a top, front and side perspective view of a helmet for security personnel, showing my new design, in one position of use;

FIG. 2 is a view similar to FIG. 1, but showing the helmet in a second position of use;

FIG. 3 is a front elevational view thereof in the position of FIG. 1;

FIG. 4 is a rear elevational view thereof;

FIG. 5 is a side elevational view thereof from the left of FIG. 3, in the FIG. 1 position, the side opposite that shown in FIG. 5 being the mirror image thereof;

FIG. 6 is a top plan view thereof in the FIG. 1 position; and

FIG. 7 is a bottom plan view thereof in the FIG. 1 position.

FIG. 1

FIG. 2

FIG. 3

FIG. 4

FIG. 5

FIG. 6

FIG. 7
